(57) **CLAIM**

The ornamental design for a label for a container, as shown and described.

DESCRIPTION

The patent or application contains at least one drawing executed in color. Copies of this patent or patent application with color drawing(s) will be provided by the Office upon request and payment of the necessary fee.

FIG. 1 is a front elevation view of a first embodiment of a label for a container showing my new design;

FIG. 2 is a rear elevation view thereof;

FIG. 3 is a left side view thereof;

FIG. 4 is a right side view thereof;

FIG. 5 is a top plan view thereof; and

FIG. 6 is a bottom plan view thereof.

FIG. 7 is a front elevation view of a second embodiment of a label for a container showing my new design;

FIG. 8 is a rear elevation view thereof;

FIG. 9 is a left side view thereof;

FIG. 10 is a right side view thereof;

FIG. 11 is a top plan view thereof; and

FIG. 12 is a bottom plan view thereof.

FIG. 13 is a front elevation view of a third embodiment of a label for a container showing my new design;

FIG. 14 is a rear elevation view thereof;

FIG. 15 is a left side view thereof;

FIG. 16 is a right side view thereof;

FIG. 17 is a top plan view thereof; and

FIG. 18 is a bottom plan view thereof.

FIG. 19 is a front elevation view of a fourth embodiment of a label for a container showing my new design;

FIG. 20 is a rear elevation view thereof;

FIG. 21 is a left side view thereof;

FIG. 22 is a right side view thereof;

FIG. 23 is a top plan view thereof; and

FIG. 24 is a bottom plan view thereof.

The broken lines of uneven length define the boundary of the claimed design and form no part of the claimed design. The broken lines of even length show unclaimed portions of the container and form no part of the claimed design.
